UNITED STATES PATENT OFFICE.

FRANK. S. CHURCH, OF DETROIT, MICHIGAN, ASSIGNOR, BY MESNE ASSIGNMENTS, TO THE AUTOMATIC STORE SERVICE COMPANY, OF PORTLAND, MAINE.

TRACK-CURVE FOR STORE-SERVICE APPARATUS.

SPECIFICATION forming part of Letters Patent No. 437,566, dated September 30, 1890.

Application filed January 30, 1890. Serial No. 338,546. (No model.)

To all whom it may concern:

Be it known that I, FRANK. S. CHURCH, a citizen of the United States, residing at Detroit, county of Wayne, State of Michigan, have invented a certain new and useful Improvement 5 in Curves for Cash and Parcel Carrier Apparatus; and I declare the following to be a full, clear, and exact description of the invention, such as will enable others skilled in the art to 10 which it pertains to make and use the same, reference being had to the accompanying drawings, which form a part of this specification.

In the drawings, Figure 1 is a plan view 15 illustrating my invention. Fig. 2 is a side elevation of the same. Fig. 3 is a detail view, and Fig. 4 likewise a detail view, of the parts of the contrivance. Fig. 5 illustrates a variation.

20 It is the purpose of my invention to produce a curve which shall be adjustable to a larger or smaller radius and adapted for use with any ordinary or novel arrangement of cash-carrier and parcel-carrier apparatus.

25 In carrying out my invention, A represents a sector pivoted at its center *a*. Upon its periphery is a series of pins *a'*.

30 *B* is a strap of spring metal—as, for instance, spring-steel—said strap extending at its ends beyond the limits of the sector A. This is provided with orifices corresponding with the pins upon the periphery of the sector, as shown at *b*, and *B'* represents pins upon the strap itself adjacent to its ends. Adjacent to these 35 pins, and between the same and the ends of the strap, there are milled channels *b'*, within which the line-wire is adjusted. These milled channels start from a point adjacent to the pin *B'*, and, passing thence toward the other

40 end of the strap, the said channels become deeper and deeper until at the upper edge it is so that it brings the wires centrally above the edge of the band at *b*². Then from this point outward to the end of the strap the upper edge of the strap is channeled to admit the wire and brings the upper surface of the wire upon the general level of the top of the band.

45 *C* is a strap of phosphor-bronze or other

suitable material, which binds the line-wire 50 upon the steel band at its extremities.

The operation of the device is as follows: The line-wire is brought over the end of the strap or band into the groove there cut for it and down through the channels *b'* beneath 55 the pin *B'*. It is then caused to pass over the next pin and under the following one, over the next, and so on to the other end of the strap, where it is carried out in the same way that it was admitted. Straps *C* are then placed 60 in position and hold the wire in place. This contrivance may be somewhat varied. Thus, for instance, the strap *B* might have a channel on its under side at *B*², as shown in Fig. 5, in which event a projecting tenon *B*³ from 65 the sector would fit within this groove to hold the strap upon the sector, and there should in that event be one protecting-pin at the center of the sector extending through a hole in the middle of the strap to prevent any longitudinal displacement of the strap along the sector or disarrangement of the sector with 70 relation to the strap. In this latter construction the wire is trained the same as before, except that it would pass over this central 75 pin at the middle of the band and beneath the pins *B'* at the two extremities of the band, as before explained.

It is obvious that in a device which is constructed according to my invention the curve 80 is made adjustable, so as to fit any angle which might be required in practice, the tension of the band itself holding it always into contact with the sector. If it is deemed best, however, there might be a screw or bolt joining 85 the band at its middle point with the periphery of the sector.

What I claim is—

1. An adjustable curve for cash or parcel carrier apparatus, the same consisting of a 90 sector A, in combination with a separate spring metallic band B, substantially as and for the purpose described.
2. The combination, with the sector and the separate spring-band, of the pins *a'*, adapted 95 to pass through the band for the purpose of holding it in place, substantially as described.
3. The combination, with the sector, of the

spring-band provided with pins B' and having channels b' b², substantially as described.

4. The combination, with the sector, of the spring-band having pins B' and provided with 5 grooves b' b², and the straps C, adjacent to the extremities of the band, substantially as described.

In testimony whereof I sign this specification in the presence of two witnesses.

FRANK. S. CHURCH.
